[57] **CLAIM**

The ornamental design for a hang up cup, as shown and described.

DESCRIPTION

FIG. 1 is a front, top, and right side perspective view showing our new design for a hang up cup;
FIG. 2 is a front elevational view thereof;
FIG. 3 is a bottom plan view thereof;
FIG. 4 is a rear elevational view thereof; and,
FIG. 5 is a left side elevational view thereof.
The broken line matter in FIGS. 1 and 5 forms no part of the claimed design. The inside right is a mirror image of the inside left as shown in FIG. 1.
